PROCESS OF PREPARING DIAZONIUM COMPOUNDS FROM 4-AMINODIARYLAMINES

Wilhelm Koch, Offenbach-on-the-Main, Germany, assignor to General Aniline Works, Inc., New York, N. Y., a corporation of Delaware

No Drawing. Application March 5, 1934, Serial No. 714,205. In Germany March 7, 1933.

1 Claim. (Cl. 260—69)

The present invention relates to a process of preparing diazonium compounds from 4-aminodiarylaminés; more particularly it relates to a process which comprises diazotizing a 4-aminodiarylamine in a reaction medium the pH-value of which is between 1 and 4.

In his publication entitled, "The Diazo Compounds of 4-Aminodiphenylamine and Its Derivatives" (inaugural dissertation, Leipzig, 1931), 10 Probst describes a series of complications which are liable to occur in the diazotization of 4-aminodiphenylamine and the derivatives thereof and which he proposes to avoid by a particular kind of diazotization. He states on page 15 of his publication that simultaneously with the diazotization another process takes place the final result of which is that part of the 4-aminodiarylamine is split with formation of a para-quinone from the aryl radical carrying the amino-group and of a diazonium compound from the second aryl radical.

It has been found experimentally that the extent of this cleavage or splitting operation largely depends on the constitution of the base. 25 Whereas, for instance, in the case of 4-aminodiphenylamine itself, only about 3 to 5 per cent. of the base are subjected to the cleavage when the work is cautiously done, other bases of this series, for instance (4'-aminonaphthyl-1')-phenylamine or 4-aminodiphenylamines having substituents in 2.5-positions, are split almost completely during the diazotization.

This invention is based on the observation that the course of the diazotization of the amino-diarylaminés depends on the acidity of the reaction medium and that no cleavage by oxidation occurs if the diazotization is carried out in a medium the pH-value of which is between 1 and 4. 35 If the pH-value is considerably below 1, cleavage occurs, whereas if the hydrogen ion concentration is too small the diazotization no longer occurs. It has been found that the cleavage does with certainty not occur at hydrogen ion concentrations which correspond to the pH-values between 40 1.5 and 4.

As reaction media there may be used aqueous solutions of salts, for instance, of zinc chloride, copper chloride, copper sulfate, ferrous sulfate or aluminium sulfate of a concentration yielding the pH-value desired, which may be determined by known methods, for instance with the aid of an ionometer; there may furthermore be used dilute acids or buffering solutions, or solutions of mixtures of acids and salts of the desired 45 50 55

pH-value. In all these cases a cleavage is entirely avoided during the diazotization.

It is strongly advisable to use the base in a state as finely divided as possible. For this purpose the base may be ground, if desired, with the addition of a suitable suspending or dispersing agent; or it may be dissolved previously in a solvent miscible with water, such as acetone or alcohol, so that if such a solution is mixed with the aqueous reaction liquid the base is obtained in a finely divided form. 5

The working methods may be varied within wide limits, as may be seen from the examples, but the invention is not intended to be limited to the particular methods described therein. By 10 diazotizing the base, for instance, in a zinc chloride solution with sodium nitrite or zinc nitrite, the zinc chloride double salts of the diarylaminé-4-diazoniumchlorides are directly obtained. 15

In the process of this invention there may, for 20 instance, be used diphenylamines or naphthyl-phenylamines or biphenyl-phenylamines and anthracylphenylamines in which an amino group stands in 4-position and which may be unsubstituted or substituted in different manner by one 25 or more substituents in the different nuclei. Suitable substituents are, for instance the following groups: alkyl, alkoxy, cycloalkoxy, aralkoxy, aryloxy, alkylcarbonyl, arylcarbonyl, alkylsulfonyl, arylsulfonyl, acylamino, substituted 30 aminocarbonyl and aminosulfonyl, alkylamino, arylamino, alkylthio and trifluoromethyl, furthermore the halogen atoms.

As is known, the bases of the 4-aminodiarylamine series have of late gained a great importance for the production of ice colors of the 35 2.3-hydroxynaphthoic acid arylamide series. The process of this invention has a high technical value. It allows of producing the diazonium salts of the bases without secondary reactions in 40 a pure form. Furthermore, it is only by employing this invention that the technical utilization of a number of bases of this kind for dyestuff manufacturing purposes has been made possible. 45

The following examples illustrate the invention. The parts are by weight unless otherwise stated:

(1) A solution of 76 parts of pure sodium nitrite in 500 parts of water is introduced drop by drop at about 30° C. in the course of about 3 hours into a suspension of 214 parts of very finely divided 4-amino-3-methoxydiphenylamine in a solution of 3000 parts of solid zinc chloride in 50 3000 parts of water. When the diazotization is 55

complete the whole is filtered. The part of the diazo salt which has already separated is extracted from the residue by treating it with warm water. The aqueous solution so obtained is combined with the filtrate and the diazonium zinc chloride double salt of the base is separated therefrom by addition of sodium chloride.

In the same manner other bases, such as (4'-amino-naphthyl-1')-4-ethoxyphenylamine, may 10 be transformed into the corresponding diazonium zinc chloride double salts without a cleavage occurring.

(2) A solution, having a temperature of about 40° C., of 242 parts of 4-amino-3-methyl-6-15 ethoxydiphenylamine in 1600 parts of denatured alcohol is quickly poured into a solution of about 30° C. of 3000 parts of solid zinc chloride and 76 parts of sodium nitrite in 3000 parts of water. After a short time the diazotization is complete 20 and the product is worked up as indicated in the preceding example.

In the same manner, other bases such as 4-amino-2,5-dimethoxydiphenylamine or 4-amino-3-methyl-4'-methoxydiphenylamine or 4-amino-25 phenyl-(6'-ethoxynaphthyl-2')-amine may be transformed into the corresponding diazonium zinc chloride double salts.

(3) A solution of about 30° C. of 184 parts of 30 4-amino-diphenylamine in 1300 parts of acetone is quickly poured into a solution of about 30° C. of 3000 parts of solid zinc chloride in 3000 parts of water. The base remains dissolved. To this solution there is added drop to drop at 25° C. to 30° C. in the course of about 10 minutes a solution of 76 parts of pure sodium nitrite in 500 parts of water.

When the diazotization is complete the product is worked up as indicated in Example 1.

(4) A solution of about 40° C. of 212 parts of 40 4-amino-2,5-dimethyldiphenylamine in 1500 parts of alcohol is quickly poured into a solution of about 30° C. of 3000 parts of solid zinc chloride and 76 parts of pure solid sodium nitrite in 3000 parts of water. After a short time the diazotization is complete. The product is worked 45 up as indicated in Example 1.

By substituting in this example for the 4-amino-2,5-dimethyldiphenylamine 268.5 parts 50 of 4-amino-3-chlorophenyl-(naphthyl-2')-amine and diazotizing in the manner described, there is obtained the diazonium zinc chloride double salt of 4-amino-3-chlorophenyl-(naphthyl-2')-amine.

For the purpose of dissolving the bases there 55 may be used other neutral organic solvents miscible with water, such as methanol, isopropyl alcohol or the like.

(5) A solution of about 40° C. of 184 parts of 60 4-amino-diphenylamine in 1300 parts of alcohol is quickly poured into a solution of about 30° C. of 350 parts of copper chloride hydrate and 76 parts of pure solid sodium nitrite in 5000 parts of water. After a short time the diazotization is complete. After filtration any diazo salt which 65 may have already been separated is extracted from the residue by treating it with warm water. The aqueous solution so obtained is combined with the filtrate and the diazonium salt is separated therefrom by adding a solution of 72 parts of solid zinc chloride in 72 parts of water and salting out with sodium chloride.

For the purpose of dissolving the base there 70 may be used other neutral organic solvents miscible with water, such as acetone, isopropyl alcohol, or the like.

In the same manner other bases, such as 75 4-amino-2,5-dimethyldiphenylamine or 4-amino-phenyl-1-([6'-ethoxynaphthyl-2']-amine), may be transformed into their diazonium compounds without cleavage occurring.

(6) A solution of about 40° C. of 214 parts of 10 4-amino-3-methoxydiphenylamine in 1500 parts of acetone is quickly poured into a solution of about 30° C. of 2800 parts of ferrous sulfate ($\text{FeSO}_4 \cdot 7\text{H}_2\text{O}$) and 76 parts of pure solid sodium nitrite in 7000 parts of water. After a short time the diazotization is complete and the product is worked up as indicated in Example 5.

Instead of ferrous sulfate there may also be 15 used solutions of, for instance, 360 parts of copper chloride hydrate in 5000 parts of water or of 3300 parts of copper sulfate hydrate in 5000 parts of water or of 530 parts of aluminium sulfate of the formula $\text{Al}_2(\text{SO}_4)_3 \cdot 12\text{H}_2\text{O}$ in 6000 parts of water, or the like.

(7) A solution of 76 parts of pure sodium nitrite in 500 parts of water is rather rapidly introduced drop by drop at about 30° C. into a suspension of 268.5 parts of very finely divided 4-amino-3-chlorophenylnaphthyl-2'-amine in a solution of 250 parts of glacial acetic acid in 5000 parts of water. When the diazotization is complete the whole is filtered. The part of the diazo salt which has already separated is extracted from the residue by a treatment with warm water. The aqueous solution so obtained is combined with the filtrate and the diazonium zinc chloride double salt is separated therefrom in the usual manner with the aid of zinc chloride and sodium chloride.

(8) 110 parts of glycocoll and 85.8 parts of 30 sodium chloride are dissolved together in water and the solution is diluted to about 20000 parts by volume. There is run into this solution a dilute hydrochloric acid which contains 80.3 parts of HCl and which has been obtained by diluting, for instance, 250.16 parts of hydrochloric acid of 20° Bé. of 32.1 per cent. by weight with about 10000 parts by volume of water. The well mixed 35 solution containing glycocoll, sodium chloride and hydrochloric acid is then adjusted with water to exactly 36666 parts by volume. The pH-value of the hydrochloric acid contained in it is now 1.5. The solution is heated to about 30° C. and 76 parts of pure solid sodium nitrite are introduced 40 into it. After a short stirring a fine suspension of about 40° C. of 214 parts of 4-amino-3-methoxydiphenylamine in 1500 parts of water is quickly added. After a short time the diazotization is complete. The resultant diazonium salt 45 may be precipitated in the usual manner.

(9) An aqueous solution of 210 parts of pure 50 crystallized citric acid, made up to exactly 10000 parts by volume, is well mixed with an aqueous solution of 286.8 parts of pure crystallized disodium phosphate, made up to exactly 4000 parts by volume. The solution thus obtained has an acidity of a pH value of 3.4. 76 parts of pure solid sodium nitrite are added and a solution of about 40° C. of 272 parts of 4-amino-2,5-diethoxydiphenylamine in 1900 parts of alcohol is rapidly run in. The whole is subsequently stirred for a short time whereupon the diazotization of 4-amino-2,5-diethoxydiphenylamine is complete. 55 After addition of the necessary quantity of a suitable mineral acid the corresponding diazonium salt may be separated in a solid form in known manner.

(10) 541.4 parts of caustic soda solution of 32.5 60 per cent. by weight (38° Bé.) are slowly run into 65 70 75

5 a solution of 462 parts of pure crystallized citric acid in about 20000 parts by volume of water. The solution of the resultant sodium citrate is then well mixed with a dilute hydrochloric acid containing 80.3 parts of HCl and obtained as described in Example 8. The mixture is made up with water to exactly 44000 parts by volume. The solution so obtained has an acidity of the pH-value=3.5. It is mixed with 76 parts of pure solid sodium nitrite and there is rapidly run into the

10 mixture a suspension, having a temperature of about 40° C., of 212 parts of 4-amino-2,5-dimethyldiphenyl-amine in 1500 parts of water. After a short time the diazotization is complete, no cleavage occurring.

5

I claim:

The process which comprises diazotizing a 4-aminodiarylamine in a reaction medium the pH-value of which is between 1 and 4.

WILHELM KOCH. 10
